UNITED STATES PATENT OFFICE.

STEWART WARING, OF EVANSTON, ILLINOIS, ASSIGNOR TO SEARS, ROEBUCK AND COMPANY, OF CHICAGO, ILLINOIS, A CORPORATION OF NEW YORK.

APPARATUS FOR TRIMMING AND MARKING WALL-PAPER.

1,274,476.

Specification of Letters Patent.

Patented Aug. 6, 1918.

Application filed June 28, 1916. Serial No. 106,337.

To all whom it may concern:

Be it known that I, STEWART WARING, a citizen of the United States, residing at Evanston, in the county of Cook and State 5 of Illinois, have invented certain new and useful Improvements in Apparatus for Trimming and Marking Wall-Paper, of which the following is a specification.

Wall paper, as heretofore manufactured, 10 has been provided with a selvage at each edge to protect the body of the paper from injury during transportation and handling. If the paper was to be used with the edges of the lengths abutting, the paper-hanger 15 was obliged to trim off both selvages. If the paper was to be hung with the edges of the lengths overlapped, the paper-hanger trimmed off one selvage, the other selvage being overlapped by the trimmed edge of the 20 adjacent length of paper.

The object of this invention is to provide means for so treating wall paper as to economize the time of the paper-hanger in hanging the paper whether the paper is to be 25 hung with edges abutting or overlapped. This object I accomplish by trimming off one selvage and by placing along the other selvage a suitable gage mark, indication or line to indicate to the paper-hanger the line 30 along which the selvage should be trimmed or overlapped.

In the accompanying drawings, Figure 1 is a fragmental top plan view of a machine embodying the features of my invention. 35 Fig. 2 is a sectional view taken in the plane of dotted line 2—2 of Fig. 1. Fig. 3 is a view looking from the left-hand side of Fig. 1. Fig. 4 is a sectional view taken in the plane of dotted line 4—4 of Fig. 1. Fig. 5 is a section on dotted line 5—5 of Fig. 1.

While the before-mentioned trimming and marking may be effected at any desired stage in the manufacture of the wall paper, these operations are conveniently performed in 45 connection with the re-rolling of the paper into rolls of the size in which the paper is to be marketed. In such re-rolling operation any suitable mechanism may be used, as for example, that shown in Patents Nos. 50 999,352 and 1,081,933, granted to me on August 1, 1911, and December 16, 1913, respectively. Herein I have shown paper-guiding rolls 1, 2, 3 and 4 located adjacent to the mechanism shown in Patent No. 55 1,081,933, said rolls being rotated through

frictional contact with the web of wall paper A passing around said rolls.

The means for trimming off one selvage comprises a circular knife 5 which is secured to a shaft 6. The shaft 6 is rotatably mounted in bearings 7 and 8. As shown in Figs. 1 and 2, the bearings 7 and 8 are attached to the supporting frame by means of thumb-screws 7^a extending through vertical slots 8^a in the supporting frame, so 60 that the shaft 6 may be raised to remove the trimming and marking devices from contact with the paper when desired. While the shaft 6 may be driven in any suitable manner, it is herein shown as continuously 65 driven by a belt 9 running over a pulley 10 on the shaft 6. The knife 5 is so located with reference to the paper that as the latter passes over the roll 2 the selvage A' is severed from the body of the web.

The means for marking the opposite margin of the web to indicate to the paper-hanger where the selvage should be trimmed off or overlapped comprises a marking disk 11 which is fixed upon the shaft 6. The 75 periphery of the disk 13 runs in contact with the web A.

Any suitable means may be employed to place a marking fluid upon the periphery of the disk 11. Herein is shown an ink 80 reservoir 12 in which is rotatably mounted a roll 13. Above the roll 13 is a roll 14. An ink-carrying tape or belt 15 runs over the rolls 13 and 14 and in contact with the periphery of the disk 11. The roll 13 is driven 85 by means of a belt 16 running over sheaves 17 and 18 fixed respectively on the shaft 6 and the shaft of the roll 13. A scraper blade 19 supported adjacent to the ascending side of the tape 15 removes surplus ink.

The paper is fed to the rolling machine intermittently, the feed of the paper being suspended while the web is being severed by the shear associated with the rolling mechanism. In the present embodiment the trimming knife 5 and the marking disk 11 rotate continuously. If the roller 2 were allowed to rotate through momentum after the feeding of the web is stopped, said roller would cause the web to become more or less 100 slack between the rolls 1 and 2. To prevent this result, I provide a brake consisting of a shoe 20 arranged to engage a wheel 21 fixed to the shaft of the roll 2. The shoe 20 is attached to a stem 22 which is mounted 105 110

for vertical reciprocation in a guide 23. At the lower end of the stem 22 is an antifriction roller 24 running upon a cam 25 fixed upon a shaft 26. The shaft 26 is so connected with the rolling machine that the brake shoe 20 is applied only when the feed of the paper is suspended.

In operation, the web A is fed into the rolling machine, being there wound into 10 rolls of the desired diameter. As the web A is fed forward into the rolling machine the selvage A' is trimmed off by the knife 5 and a gage line A² is printed along the other selvage by the disk 11. Whenever the feed 15 of the paper stops, the brake shoe 20 is applied to the wheel 21 to prevent the paper from being slackened through momentum rotation of the roll 2.

I claim as my invention:

20 1. A wall-paper trimming and marking machine comprising a surface over which the paper runs, a shaft extending transversely of the paper, a marking disk and a circular knife mounted on said shaft in peripheral contact with the selvages of the paper lying upon said surface, means for conveying color to the periphery of the marking disk, and means for rotating the shaft.

25

2. A wall-paper trimming and marking 30 machine comprising a roll over which the paper is drawn, a marking disk and a circular knife, supporting means for the disk and the knife, means for rotating the disk and the knife in peripheral contact with the 35 selvages of the paper lying upon said roll, and means for conveying color to the periphery of the marking disk.

3. A wall-paper trimming and marking 40 machine comprising a surface over which the paper runs, a marking disk and a circular knife, supporting means for the disk and the knife, means for rotating the disk and the knife in peripheral contact with the 45 selvages of the paper lying upon said surface, and means for conveying color to the periphery of the marking disk.

4. A wall-paper trimming and marking machine comprising a surface over which the paper runs, a selvage-marking device 50 and a selvage-trimming knife, means for supporting said device and knife in operative relation to the selvages of the paper running over said surface, and means for actuating the marking device and the knife. 55

In testimony whereof, I have hereunto set my hand.

STEWART WARING.
